(Cl. D57—1)

To all whom it may concern:

Be it known that I, Neil Kenneth Glynne Rosser, a subject of the Queen of Great Britain, residing at Ditton Corner, Herne Road, Long Ditton, in the county of Surrey, England, have invented a new, original and ornamental Design for a Spectacle Frame, of which the following is a specification, reference being made to the accompanying drawings, forming a part thereof.

In the drawings:

Figure 1 is a front perspective view of a spectacle frame, showing my design;

Figure 2 is a rear elevational view thereof; and
 Figure 3 is a rear perspective view thereof.

I claim:

The ornamental design for a spectacle frame, substantially as shown.

N. K. G. ROSSER.
